US0D1099019S

(12) **United States Design Patent** (10) Patent No.: **US D1,099,019 S**
(45) Date of Patent: ** Oct. 21, 2025

(54) **CHARGING STATION**

(71) Applicant: **XCHARGE ENERGY USA INC.**, San Marcos, TX (US)

(72) Inventors: **Rui Ding**, San Marcos, TX (US); **Xiaoran Du**, San Marcos, TX (US)

(73) Assignee: **XCHARGE ENERGY USA INC.**, San Marcos, TX (US)

(**) Term: **15 Years**

(21) Appl. No.: **29/910,645**

(22) Filed: **Aug. 22, 2023**

(51) LOC (15) Cl. **13-02**

(52) U.S. Cl.

USPC **D13/107**

(58) **Field of Classification Search**

(57) **CLAIM**

The ornamental design for a charging station as shown and described.

DESCRIPTION

FIG. 1 is a top perspective view of a charging station according to our new design;

FIG. 2 is a bottom perspective view thereof;

FIG. 3 is another top perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate portions of the charging station that form no part of the claimed design.

1 Claim, 9 Drawing Sheets
